(57) **CLAIM**

The ornamental design for a toy aircraft as shown and described.

DESCRIPTION

FIG. 1 is a front, right, top perspective view of a toy aircraft showing my new design;

FIG. 2 is a rear, left, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and, FIG. 10 is an enlarged view of portion 10 shown in FIG. 2. The dash-dash broken lines in the drawings depict portions of the toy aircraft that form no part of the claimed design. The dot-dash broken lines shown are for purposes of annotating the enlarged view only and form no part thereof. The unshaded surfaces between solid and evenly-spaced broken lines in FIGS. 2-6, and 8, form no part of the claimed design.
